PRODUCTION OF NITRIC ACID

Nicolay Titlestad, White Plains, N. Y., and Arthur C. Bright, Piney River, Va., assignors to Chemical Construction Corporation, New York, N. Y., a corporation of Delaware

Application January 20, 1939, Serial No. 251,882

3 Claims. (Cl. 23—162)

This invention relates to a process and apparatus for the production of nitric acid. In particular it relates to the compression of nitrogen oxides for the subsequent pressure absorption of the same to produce nitric acid.

5 The apparatus involved in a known nitric acid system is comprised essentially and in the order named, of an ammonia burner containing a platinum gauze catalyst, a cooler such as a waste heat boiler, a condenser, a compressor, an oxidizer and a pressure absorption tower.

10 The process of producing nitric acid in such a system comprises the following sequence of steps. Ammonia is oxidized with air on the platinum gauze to produce a hot gas containing nitric oxide and water vapor and this hot gas coming from the ammonia burner is cooled and heat recovered therefrom in the form of steam by passing the hot gas through a waste heat boiler. Thereafter the partially cooled gas is passed 15 through a condenser operated at relatively low temperatures to remove a major part of the water therefrom, whereupon the gases in a separate step are compressed to a high pressure, for example to several atmospheres, subjected to an 20 oxidation step if necessary, and then absorbed in the tower with a weak nitric acid and/or water under the pressure produced by the compression step.

25 In plants employing the above process the gas is ordinarily compressed by a centrifugal or reciprocal type compressor. Centrifugal compressors have been used in large capacity plants, but they are not economical in plants of low capacity, i. e., those having a small gas volume due to 30 their high initial cost. Reciprocal type compressors have been suggested as a substitute in smaller plants, but the problem of lubricating the pistons of such compressors is still a serious one. One of the chief difficulties in the lubrication 35 of this type of compressor is the destruction of the lubricant due to its carbonization by the nitric acid formed when compressing the moist nitrogen oxides.

40 It is the object of our invention to use an hydraulic compressor to compress the nitrogen oxides in such a nitric acid system. By the use of an hydraulic compressor the condensation of water from the gas and its compression may be effected in a single operation. The use of an 45 hydraulic compressor offers a practical solution to the problem of compressing the gas in a plant of small gas volume, since the lubricant does not come in contact with nitric acid.

50 In the accompanying drawing we have illus-

trated diagrammatically an apparatus designed for the carrying out of our invention and in which Fig. 1 is a representation of a nitric acid system showing one type of hydraulic compressor and Fig. 2 is a modified form of hydraulic compressor. It is to be understood that all the parts of such a nitric acid system are not illustrated in the drawing but only those necessary to point out the invention.

55 Referring to Fig. 1 there is diagrammatically shown therein an ammonia burner containing a suitable catalyst such as platinum gauze together with a waste heat boiler, an hydraulic compressor denoted generally at 1, an oxidizer and a high pressure absorption tower. The hydraulic compressor 1 consists of an aspirator head 3 of standard construction, a vertical feed pipe 4 for carrying compressing liquid thereto, a water cooling jacket 5 on pipe 4, and a centrifugal pump 6 connected at its discharge side with pipe 4. A pipe 7 is shown connected to the discharge side of the aspirator head 3 and with a gas and liquid separation tank 8 of a construction suitable for the disengagement of the compressed gases from the compressing liquid. Pipes 9 and 10 are shown as connected to the tank 8 and to the oxidizer and absorption tower respectively for the passage of disengaged and compressed gas on the one hand and a portion of the liquid from tank 8 on the other hand. Pipe 11 is provided for the return by means of centrifugal pump 6 of liquid from the tank 8 to the compressing cycle. A means is provided for the introduction of water into the system for use as initial compressing liquid; such a means may be that as indicated on line 11 between the pump 6 and the separation tank 8.

60 Assuming that ammonia has been oxidized with the reaction proportion of air in the ammonia burner to give a hot gas containing nitrogen oxide and water vapor and that the hot gas has been partially cooled in the waste heat boiler, the operation of the hydraulic compressor to remove water from and to compress the gases in accordance with my invention is as follows:

65 The hot gas from the waste heat boiler is passed through pipe 2 and enters the aspirator head 3 at an elevated temperature and preferably above the dew point of the gas. In the aspirator head the hot gas will encounter a stream of cool 50 weak nitric acid supplied by pump 6 through pipe 4, the acid moving at a velocity head sufficient for the aspiration and compression of the gas. The centrifugal pump will be operated at a pressure and volume of weak acid sufficient 55

to create the necessary velocity head, and the acid moving through pipe 4 will be cooled by the water jacket 5. The hot gas on encountering the rapidly moving stream of weak nitric acid in the aspirator head will be cooled and mixed therewith, the mixture of gas and acid moving down through pipe 7 into separation tank 8 where the compressed gas will be disengaged from the compressing acid and the condensed water. The separated compressed gas will then be passed through pipe 9 to the oxidizer and eventually to the absorption tower while some of the weak acid from the separation tank will be passed to the absorption tower for the absorption therein of the compressed and oxidized nitric oxide under the high pressure resulting from the compression of the gas to produce nitric acid. The oxidizer and absorption tower may be operated in accordance with known practice.

In Fig. 2 we have shown a modified design of hydraulic compressor for use in the above described nitric acid systems and in which the ammonia oxidation gases passing through pipe 2 from the waste heat boiler will be cooled by a water jacket 13 and water condensed therefrom before they enter the aspirator head. A chamber is shown at 14 and a pipe at 15 for the collection and removal of condensed water to an absorption tower. In this modification the gas and liquid separation tank 16 is not provided with a pipe for removal of liquid therefrom to an absorption tower since we contemplate the removal of sufficient water from the gas by cooler 13.

The design of the gas and liquid separation tank is such as to allow of disengagement of the compressed gas from the acid and it conceivably may take the form of a flash separator or of a single chamber in which may take place the disengagement of the gas from the compressing acid and absorption of the separated gas to produce nitric acid.

From the foregoing it will be seen that a specific embodiment of the invention has been described which accomplishes all the objects thereof. This embodiment has been described as operating on oxides of nitrogen from the catalytic oxidation of ammonia, since this is a representative gas source. It should be understood, how-

ever, that the invention is equally well adapted to the compression and subsequent oxidation and absorption of oxides of nitrogen from other sources, such as from the denitration of spent nitrating acid, from the arc process, or in general from any source in which oxides of nitrogen are produced in commercially useful quantities.

It should also be understood that the invention in its broader aspects is not restricted to the specific details which have been described and shown, but that it is limited only by the scope of the following claims.

What we claim is:

1. An apparatus for the production of nitric acid comprising in combination an ammonia burner, a gas cooler, an hydraulic compressor directly connected with the gas outlet of the gas cooler, the hydraulic compressor comprising a centrifugal pump, an aspirator head, a vertical conduit connecting the pump with the aspirator head, means for cooling the aqueous compressing liquid, an oxidizer, and a pressure absorption tower.

2. A process of producing nitric acid which comprises condensing water from and compressing a relatively cool gas containing lower oxides of nitrogen in a single operation by hydraulically compressing it with a cool aqueous liquid moving under pressure, disengaging the compressed gas from the compressing liquid, oxidizing lower oxides of nitrogen in the gas to nitrogen peroxide, and absorbing the nitrogen peroxide in an aqueous absorbing medium under pressure to form nitric acid.

3. A process of producing nitric acid which comprises oxidizing ammonia to form a hot gas containing lower oxides of nitrogen and water vapor, partially cooling said gas, condensing water from and compressing said partially cooled gas in a single operation by hydraulically compressing it with a cool aqueous liquid moving under pressure, disengaging the compressed gas from the compressing liquid, oxidizing nitric oxide in the compressed gas to nitrogen peroxide, and absorbing the nitrogen peroxide in the gas under high pressure to form nitric acid.
